Patented Apr. 19, 1927.

UNITED STATES PATENT OFFICE.

ALFRED J. REEDY, OF BATTLE CREEK, MICHIGAN, ASSIGNEE TO A. B. STOVE COMPANY, OF BATTLE CREEK, MICHIGAN.

STOVE-DOOR CONSTRUCTION.

Application filed April 23, 1926. Serial No. 104,071.

The main object of this invention is to provide an improved stove door structure which may be provided with an enamel or like finish which is protected so that it is not likely to be chipped or broken as a result of closing or slamming the door to insure against breaking of enamel or peeling of nickel when grinding the door to fit against its casing or front.

10 Objects pertaining to details and economies of my invention will definitely appear from the detailed description to follow. The invention is clearly defined and pointed out in the claims.

15 A structure embodying the features of my invention is clearly illustrated in the accompanying drawing forming a part of this application, in which:

Fig. 1 is a fragmentary front perspective view of a gas range embodying the features 20 of my invention.

Fig. 2 is a fragmentary section on a line corresponding to line 2—2 of Fig. 1.

Fig. 3 is an enlarged fragmentary section 25 of the door frame.

In the accompanying drawing I illustrate only such parts of a stove structure as are deemed necessary to illustrate an embodiment or adaptation of my improvements.

30 1 represents an oven, 2 a broiling chamber below the oven, and 3 the open cooking top at the side of the oven. The oven is provided with a door frame 4. The doors are designated generally by the numerals 5 and 6 and a description of one will suffice.

35 These doors are mounted to close against the door casing. My improved door as illustrated comprises a rectangular cast iron frame 7 which is of inwardly curved cross section as shown in Fig. 2 providing an inwardly facing outer edge 8 adapted to close against the face 9 of the door casing. The door panel 10 and the lining 11 are mounted in this frame in any suitable manner.

40 45 The frame is provided with a finish, preferably enamel, indicated at 12 and has a rabbet-like recess 13 extending around the same, thereby providing a bumper portion 14 of less width than the thickness of the frame. The enamel, nickel or other suitable finish overlaps the shoulder of the rabbet but does not extend to the inner edge of the door frame. This spacing of the finished surface from the door casing engaging face

protects the finish from blows such as would result from the slamming of the door, which in the event of the door being finished with enamel or nickel extending to the edge of the door, is quite likely to crack and chip the enamel or peel the nickel. It also provides a projecting portion which may be ground as necessary to cause the same to properly fit or close against the casing without danger of injuring the enamel or peeling the nickel.

50 My improvement is of very substantial advantage from the manufacturer's standpoint in that it enables the enameling of the frame and completing of the doors prior to the grinding necessary to cause the same to properly fit or close, and also protects the enamel or other finish, as stated, from injury occasioned by slamming of the doors.

55 My improvement is capable of embodiment in a great variety of forms or adaptations but it is believed that it is unnecessary to illustrate the same, and that this disclosure will enable those skilled in the art to embody or adapt my improvements as may be desired.

60 Having thus described my invention what I claim as new and desire to secure by Letters Patent is:

65 1. A structure of the class described comprising a door casing, and a door mounted to close against said casing and comprising a frame having an enameled outer surface, the frame being curved in cross section providing an inwardly facing outer edge closing against said casing, the frame being rabbeted on the outside at the edge thereof, the enamel extending over the inwardly facing shoulder provided by the rabbet.

70 2. A structure of the class described comprising a door casing, and a door mounted to close against said casing and comprising a frame having an inwardly facing outer edge rabbeted on the outside thereof to provide an inwardly facing frame engaging casing offset from the external surface of the frame.

75 3. A structure of the class described comprising a door casing, and a door mounted to close against said casing and comprising a frame curved in cross section providing an inwardly facing outer edge closing against said casing, the frame being rabbeted on the outside at the edge thereof, the frame surface finish extending into the rabbet.

4. An enameled stove door unit having an inwardly facing outer edge with a rabbet-like recess at the outer side thereof, the enamel extending into the recess but terminating short of the face of the edge.

5. A stove door unit having an inwardly facing outer edge with a rabbet-like recess

at the outer side thereof, the outer surface having a finish extending into the recess of the edge.

In witness whereof I have hereunto set my hand.

ALFRED J. REEDY.
